Specification for Design.

Patented May 18, 1920.

Application filed September 25, 1919. Serial No. 326,399. Term of patent 3½ years.

To all whom it may concern:

Be it known that I, THOMAS DELIKAT, a citizen of Poland, and a resident of Newark, in the county of Essex and State of New Jersey, have invented a new, original, and ornamental Design for a Spring Support and Hanger, of which the following is a specification, reference being had to the accompanying drawing, forming part thereof.

The figure is a side view of a spring support and hanger, showing my new design.

I claim—

The ornamental design for a spring support and hanger as shown.

THOMAS DELIKAT.
